UNITED STATES PATENT OFFICE.

LOUIS J. MONAHAN AND CONRAD KIEREN, OF OSHKOSH, WISCONSIN,
ASSIGNORS OF ONE-THIRD TO EMIL H. STEIGER, OF FREMONT, WIS-
CONSIN.

MACHINE FOR MAKING TWINE.

SPECIFICATION forming part of Letters Patent No. 697,411, dated April 8, 1902.

Application filed March 4, 1899. Serial No. 707,759. (No model.)

To all whom it may concern:

Be it known that we, LOUIS J. MONAHAN and CONRAD KIEREN, citizens of the United States, residing at Oshkosh, county of Winnebago, 5 State of Wisconsin, have invented new and useful Improvements in Machines for Making Twine, of which the following is a specification.

Our invention has relation to machines for making twine, the invention having particular reference to machines for making grass twine.

The primary object had in view is to produce an improved form of machine which will 15 make a uniform size of twine and also a machine in which all the working parts are readily accessible for adjustment or repairs.

The invention furthermore contemplates as objects the provision of a construction where- 20 by little or no slippage of the tension is required, to provide for readily removing an exhausted spool and replacing it with a new spool, and to provide for applying the thread closer to or farther away from the twister.

With the above and other incidental objects in view the invention consists of the devices and parts or their equivalents, as hereinafter more fully set forth.

In the accompanying drawings, Figure 1 is 30 a side elevation of the machine. Fig. 2 is a plan view of Fig. 1. Fig. 3 is a detail view of the nipper, showing the same in connection with the drum, a fragmentary section only of the drum being shown. Fig. 4 is a side elevation of the feeding mechanism. Fig. 5 is a 35 plan view of Fig. 4. Fig. 6 is a plan view of the twisting and thread-carrying mechanism. Fig. 7 is a longitudinal sectional view of Fig. 6. Fig. 8 is a section on the line $y-z$ of Fig. 40 7, and Fig. 9 is a front view of the twister.

All the working parts of our machine are supported on suitable framework of any desirable and convenient construction. Mounted in a bearing in this frame is a shaft, which 45 carries two disks N. Pivoted to the inner face of each disk, near the peripheral edge thereof, are a series of fingers s, the pivot of each finger being advisably at a point between the ends of the finger. Mounted ad- 50 justably on extensions from the frame by

means of set-screws and adjacent to the inner faces of the disks N are cams $t-t$ of the contour clearly shown in Fig. 4. Also mounted on one end of the disk-shaft is a pulley r' and adjacent to said pulley a bevel-gear Q, 55 with which another bevel-gear (not shown) is in mesh for the purpose of imparting rotation to the shaft. Any other desirable means, of course, for rotating the shaft may be provided.

The endless conveyer-belt is indicated by the letter u, said belt passing around suitable belt-pulleys, as shown in Fig. 4. The inner end of this belt extends partly beneath the feeding-fingers s, and this tends to keep 65 the material under the fingers at a regular tension. On one end of the shaft of the forward pulley of the conveyer u is mounted a pulley r , which is connected to the pulley r' on the disk-shaft by means of a crossed belt. 70 (Shown in dotted lines in Fig. 4.) By this means the rotation of the disk-shaft is caused to move the conveyer in a direction to bring the material carried thereon beneath the fingers s.

The letter A indicates a drum, which is mounted fast on a shaft journaled in suitable bearings in the framework. This shaft may be driven by any desirable means; but we have shown as mounted on one end thereof a 80 worm-wheel A', which may be geared into a worm for the purpose of imparting the necessary rotation. The periphery of the drum A is formed with a series of lines of diagonally-arranged openings, as most clearly 85 shown in Fig. 2, and one peripheral edge of the drum is formed or provided with an annular flange, through which openings are formed, as most clearly shown in Figs. 1 and 3. The drum A carries a series of nippers, 90 each nipper comprising a pivoted jaw V and a stationary jaw V'. This stationary jaw may be a continuation of or an integral part of a standard U, said standard being passed through one of the holes in the periphery of 95 the drum and being held thereto by means of nuts engaging the inner threaded end and turned against the inner side of the periphery of the drum, a shoulder on the standard clamping the outer side of the periphery of 100

said drum. The movable jaw V is pivotally connected to a sliding rod T, which rod extends through the standard U and through one of the openings in the flange of the drum A. The outer end of each rod T is of hook form, and to this hook is connected one end of a coiled extension-spring R, the opposite end of said spring being connected to another hook, as clearly shown in Fig. 3. This spring effects the function of normally holding the pivoted or movable jaw in closed engagement with the fixed jaw. One of the jaws of the nipper has projecting therefrom a lug W, the end of said lug fitting in a recess in the other jaw. This lug is so spaced from the ends of the jaws of the nipper as to provide a space only sufficient to admit one length of the material to pass between the jaws.

Beneath the drum A are guide-plates F F, said plates being of any desirable material, but preferably of steel. These plates are supported by means of brackets E E. Pivoted to the upper plate F, near the end thereof which is farthest from the feeding mechanism, is an abutment v, which is forced downwardly to the position shown in Fig. 4 by means of a spring w, the tension of said spring being regulated by means of a screw x. It will be understood that the grass or other material is forced by the fingers s into the space between the plates F F and beneath the drum A. The tension of the spring w is sufficient to retain between the plates the proper amount of the grass or other material. If, however, too much grass or material is fed between the plates F, the abutment v is raised by the pressure of the material and the surplus material thereby permitted to discharge.

Suitably supported by the frame are cams D D' and are preferably of the form of anti-friction-rollers. These cams are arranged at the point where the nippers are required to open. Heretofore stationary cams have been employed for the purpose of opening the nippers, but these have been found objectionable owing to the excessive wear which they produce on the nippers. By providing cams of the form of anti-friction-rollers friction and wear are very materially reduced.

Arranged beneath the drum A is an inclined pan or receptacle G, which is to receive the grass as it is released by a nipper and to conduct the same to the twisting mechanism.

Referring now to the twisting mechanism, the letter H² indicates a shaft rotated by any suitable means, preferably by means of a pulley H', around which a belt (not shown) leading from any suitable source of power may pass. Within the shaft H² is formed or provided a conical passage. The conical passage serves the function of receiving the grass from the pan G. Fastened to or in one with the shaft H' is a disk H. Pivoted to this disk are jaws c c', and fast to said jaws or integral therewith are projecting arms d² d², which form in connection with the jaws bell-crank levers. Adjustably mounted on the

arms d² d² are weights d d'. If the arms d² and the weights d d' were not employed, the centrifugal force, caused by the rapid rotation of the twister, would cause the jaws to fly outwardly, and thus lose their power to twist properly. To overcome this, we have provided the said arms d² and weights d d', said weights being adjusted in a position to counteract the centrifugal force. The jaws are acted upon by springs b b', which springs tend to hold the jaws together while effecting the function of twisting. The tension of the springs may be regulated by means of screws e.

The letter K indicates a thread-carrying shaft, which is mounted in a suitable upwardly-extending bearing. This shaft carries a pulley K', around which a belt is adapted to be passed for transmitting rotation to the shaft. A spool of thread I is fitted on the shaft K, said spool bearing at one side against an annular shoulder formed on the shaft and having a nut g turned against its opposite side.

The letter J indicates a tension-carrying shaft, which extends through the shaft K, its opposite ends projecting beyond the ends of said shaft K. On one projecting end is mounted a pulley J', around which a belt is adapted to be passed for the purpose of rotating the shaft. The other projecting end of the shaft carries a tension f, which tension is advisably in the form of a split collar, which may be slipped on the shaft or screwed fast to the shaft, as the case may require, as it is one of the objects of this invention to run the tension without slipping when possible. This object is accomplished by driving the tension-carrying shaft J slower than the thread-carrying shaft K. Extending from the tension-collar f is a spring-arm h, which is formed at its free end with a hook. The thread from the spool I is made to engage this hook and is then extended to position for being wrapped around the twisted grass.

In order to remove the spool I when necessary to replace it with a new spool, we provide an adjustment of the standard, which forms a bearing for the thread-carrying shaft K. This standard is normally held by means of a pin n. In order to adjust the standard farther away from the twister, so as to provide room for removing the spool I, a pivoted lever l is manipulated, the pivot of the lever being designated by the letter m. This manipulation after the pin n has been removed, as aforesaid, will cause the standard and parts carried thereby to be slid along the base a. The spool can then be removed and a new one substituted. The lever l is then manipulated in the opposite direction to bring the parts back to their former position, and after this the pin n is again inserted in place.

Where it is necessary to make stronger twine for different purposes, the thread must be applied closer to the twister. To provide for this, a plate o is seated in a recess in the

base *a*, and this plate is somewhat less in length than the length of the recess. The plate is provided with an elongated opening through which a set-screw *p* is passed and is turned into the base *a*. Whenever this set-screw is loosened, the plate *o*, and consequently the standard which forms a bearing for the shaft *K*, can be moved toward the twister, together with said shaft *K* and the other parts. After the required adjustment is obtained the screw *p* is again tightened.

The letter *M* indicates a rotatable draw-wheel, which serves the function of drawing the material from the pan *G* through the twister and finally through the bore of the shaft *J*, the finished article being then wound on balls or other convenient devices. The wheel *M* may be rotated in any desirable manner; but we have shown teeth thereon adapted to be engaged by a worm mounted on a short shaft, said shaft carrying a pulley, around which a belt is adapted to be passed for rotating the shaft.

In the operation of our machine the material, preferably grass or hay, is placed on the belt *u* and is conveyed by said belt in a direction to be acted upon by the fingers *s*. At the same time the disks *N*, carrying the fingers *s*, are rotated in a direction to cause the engagement of said fingers with the material so carried by the conveyer. These fingers catch the material and carry it along between the plates *F*, the part *v* acting as an abutment to hold the material back under the drum *A* at a proper tension. The fingers *s*, as previously explained, are pivoted or hung loosely on the disks *N*, and the upper ends of the fingers come in contact with the cams *t* and are thereby prevented from swinging back while forcing the material forward. After a finger has been carried sufficiently far to cause its upper end to disengage from a cam said finger is permitted to tip back, and thereby slip out of the material without breaking or injuring the material. The cams *t* may be adjusted by loosening the set-screws which hold the same and moving said cams forward or backward to thereby permit the fingers *s* to leave the material earlier or later, as may be required, whereby the length of time of the engagement of the fingers with the material is regulated and the danger of injuring or breaking the material thereby avoided. Where stiff grass is used, it is particularly important that this adjustment of the cams be provided for. As the drum *A* rotates the inner end of the rod *T* of one of the nippers will be brought into engagement with the cam *D*, and this will cause a turning of the pivoted jaw *V* and a consequent opening of the nippers. This will permit one length of the grass or material to be admitted between the jaws of the nipper, the lug *W*, as previously explained, limiting the space between the jaws to such an extent as to only admit one length of the material. With the continued rotation of the drum *A* the rod *T* leaves the cam *D*, and the pivoted

jaw *V* then immediately closes by the action of the spring *R* and securely holds the single length of grass. When the nipper referred to reaches the cam *D'*, the rod *T* is again acted upon and the nipper thereby opened and the length of grass deposited in the pan *G*. All the several nippers carried by the drum are acted upon in the same manner and the lengths of grass deposited in the pan *G* in the manner pointed out. At the beginning of the operation of the machine the first few lengths of grass are forced by hand between the jaws *c c'*, and until the material reaches the required length to extend to the draw-wheel *M* it must be pulled through the tubular shaft *J*. It will be understood, however, that when the material is of a length to engage the draw-wheel *M* the operation of the machine thereafter is entirely automatic, the grass being fed into the pan *G*, thence sliding down said pan into the conical passage of the shaft *H²*, thence being drawn between the jaws of the twister, and finally drawn through the tubular shaft *J* by the action of the draw-wheel *M*. As the grass is firmly clamped and held by the jaws *c c'* and as the disk *H* carrying said jaws in the operation of the machine is rotating, it is obvious that the lengths of grass are necessarily tightly twisted together. It will also be understood that at the first starting of the machine the thread from the spool *I* is wound slightly by hand around the twisted grass. The rotation of the thread-carrying shaft *K* continues the winding of the thread throughout the further operation of the machine, the winding of the thread around the twisted grass holding the twisted strands of the grass together.

The spring *h*, carried by the tension *f*, compensates for any slight jerks that may occur, and thus saves the thread from breaking.

It will be understood that the shaft *J* is driven in the same direction as the shaft *K*; but in order to obviate the necessity of the tension slipping, as has heretofore been found necessary in order to wind the thread on the twine, we prefer to drive the tension-carrying shaft *J* at a slower rate of speed than the thread-carrying shaft *K*.

Attention is further directed to the fact that the shaft *H²*, which carries the twister, is rotated in an opposite direction to the tension and spool-carrying shafts.

Inasmuch as the tapering passage is located in the shaft *H²* it is obvious that said passage is constantly revolving during the operation of the machine. This presents an advantage, inasmuch as said passage is thereby kept in line with the twister-jaws at all times. In other words, if the tension-carrying shaft and the spool-carrying shaft are run in the same direction and at the same rate of speed it is absolutely necessary that provision should be made for the tension slipping, as otherwise the thread would not wind around the lengths of the material. It is desirable to do away

with the necessity for providing for the slipping of the tension, and we have therefore obviated this difficulty by running the tension-carrying shaft at a slower rate of speed 5 than the spool-carrying shaft and that by a fine adjustment of the speeds there will be no slippage required. Of course by this arrangement a continual lessening in the tension on the thread would occur were it not 10 for the fact that the slack so produced is taken up by the winding of the thread around the lengths of the material. It will also be noticed that in our construction the tapering passage extends a slight distance into the space between the two jaws, so that the feeding of the 15 lengths of grass to the jaws is insured.

Having fully described our invention, what we claim, and desire to secure by Letters Patent, is—

- 20 1. In a machine for making twine, the combination, of movable conveying mechanism, a rotatable part, fingers loosely hung on said rotatable part, said fingers adapted to engage and feed the material carried by the conveying mechanism, and an adjustable cam with which the fingers are adapted to make direct contact while said fingers are engaging the material.
- 25 2. In a machine for making twine, the combination, of a twister, means for rotating the same, a tension-carrying shaft, a tension device carried thereby, a spool or thread carrying shaft, means for rotating the tension-carrying shaft, and means for rotating the 30 spool or thread carrying shaft at a faster rate of speed than the tension-carrying shaft, said tension-carrying shaft and the spool or thread carrying shaft being rotated in the same direction with each other, but in a different direction from the twister.
- 35 3. In a machine for making twine, the combination, of a tension-carrying shaft, a tension device carried by the shaft, said tension device consisting of a split collar engaging 40 the shaft and adapted to be held thereto by

friction, means for adjusting the friction of the collar, a thread-carrying shaft adapted to rotate about the tension-carrying shaft, and a spring-arm extending from the split collar, said arm adapted to carry and take the thread 50 from the thread-carrying shaft.

4. In a machine for making twine, the combination, of means for forming lengths of material into twine, a bearing, a shaft journaled in said bearing, a spool of thread 55 removably mounted on the shaft, and means for releasably holding the bearing, whereby when the holding means is released the bearing can be adjusted farther away from the twine-forming mechanism in order to permit 60 of the removal of the spool and the substitution of a new spool.

5. In a machine for making twine, the combination, of means for forming the lengths of material into twine, a standard, a tension-carrying device and a spool-carrying device carried by the standard, an adjustable plate, a connection between the plate and the standard, and means for holding the plate in adjusted position, whereby the tension-carrying 65 device and the spool-carrying device are brought closer to or farther away from the twine-forming mechanism.

6. In a machine of the class described, a wrapping mechanism comprising a tubular 75 shaft, the material to be wrapped arranged to pass longitudinally through said shaft, a tension device loosely mounted on said shaft and held thereto by friction, a thread-carrying shaft sleeved upon the tension-carrying shaft, 80 a thread or cord guide carried by the tension device, and means for adjusting the frictional engagement of the tension device with its shaft.
